OTHER PUBLICATIONS

U.S. Appl. No. 29/451,514, entitled "Retractable Light", filed Apr. 3, 2013, 8 pages.

Primary Examiner — Brian N Vinson

(74) Attorney, Agent, or Firm — Brooks Kushman P.C.

(57) **CLAIM**

The ornamental design for a retractable light, as shown and described.

DESCRIPTION

FIG. 1 is a top plan view of a retractable light showing my new design;

FIG. 2 is a rear elevational view thereof;

FIG. 3 is a left side elevational view thereof;

FIG. 4 is a front elevational view thereof;

FIG. 5 is a right side elevational view thereof; and,

FIG. 6 is a bottom plan view thereof.

The broken line disclosure represents portions of the retractable light which form no part of the claimed design.
